F. P. TERRY

FURNACE IGNITER

Filed Aug. 10, 1925

UNITED STATES PATENT OFFICE.

FREDERICK P. TERRY, OF ALAMEDA, CALIFORNIA.

FURNACE IGNITER.

Application filed August 10, 1925. Serial No. 49,491.

This invention relates to ignition systems and is particularly applicable to furnaces for heating purposes.

Prior to my invention gas furnaces have been provided with electrical ignition means and with a fuel valve having electrically controlled operating mechanism. The circuit of this operating mechanism was opened and closed by a switch, located at a point 10 comparatively remote from the furnace. This switch was usually of the push button type, and when it was desired to place the furnace in operation, this switch was pressed and released. By pressing the switch a 15 circuit was closed which caused the valve to open and which created a spark adjacent the burner of the furnace to ignite the fuel. The duration of the ignition spark, however, was only for the period during which 20 the circuit was maintained closed by the operator pressing the button. In some cases the operator would not hold the circuit closed for a time sufficient to cause ignition of the fuel. This had very disastrous results 25 as it caused the furnace and flues to be filled with unburned gas which if ignited caused explosions.

It is the principal object of the present invention to overcome this disadvantage in 30 prior devices by providing an ignition system wherein the ignition spark will endure for a predetermined length of time, regardless of how long the operator maintains the valve operating circuit closed.

In carrying out this object, I provide a 35 main circuit for actuating the control valve mechanism, which circuit may be closed from a point remote from the furnace. I also provide an ignition circuit which will be 40 closed simultaneously with the main circuit, but which will be automatically opened independently of the main circuit after the lapse of a predetermined interval of time. In this way I insure that the igniting spark 45 will be of sufficient duration to ignite the fuel delivered to the burner.

One form which the invention may assume is exemplified in the following description and illustrated by way of example in the 50 accompanying drawings, in which:

Fig. 1 is a diagrammatic view disclosing my improved system.

Fig. 2 is a view in elevation and partly in section disclosing the mechanism by which 55 I close and open the ignition system.

Referring more particularly to the accompanying drawings, 10 indicates the fuel control valve of a furnace or other apparatus to which my improved ignition system is applicable. This valve may be of any type 60 having a rotatable valve controlling the communication between a fuel supply pipe 11 and a pipe 12 for conveying the fuel to the burners of the furnace. Valves of this type are in common use and for this reason 65 it is merely diagrammatically illustrated. It should be stated, however, that the valve member is formed with three ports of different area so that three different quantities of fuel may be delivered to the pipe 70 12. That is to say, the valve may be entirely closed and upon three successive quarter revolutions thereof its different ports will successively register with a port communicating with the pipe 12. Upon the fourth 75 quarter revolution, the valve will again entirely shut off communication between the pipes 11 and 12.

To operate the valve 10, it is fitted with a 80 rotatable shaft 14 upon which a gear 15 is loosely mounted. The teeth of this gear mesh with rack teeth formed on the core 16 of a solenoid magnet 17. When a circuit is completed through the solenoid the core 16 will move axially a distance sufficient 85 to rotate the gear 15 one-quarter of a revolution. This motion is transmitted to the shaft through a pawl 18 on the gear and a ratchet 19 fixed on the shaft. The moment that the circuit through the solenoid is broken, 90 the core 16 and the gear 15 return to normal position but the shaft remains stationary.

One side of the solenoid is grounded. The other side is led to a push button switch 20 and thence to a transformer 21 which may 95 derive current from any desired source. The transformer is provided for the reason that most buildings equipped with furnaces in connection with which my system will be employed, are provided with 110 volt circuits. As my apparatus uses less voltage than this, a transformer to cut down the voltage is employed.

It is intended that when the valve is 100 moved from closed to its first open position that a spark be created adjacent the furnace burners simultaneously with the opening of the valve to ignite the fuel delivered through the pipe 12. For this purpose, one side of 105 the transformer 21 is connected with a spark 110

- coil 22. One terminal of this coil is led to an ignition plug 23 the other side of which is grounded. The circuit of this plug is normally open and is controlled by a switch 24. 5 This switch comprises a movable spring contact arm 25 and a stationary arm 26 which is connected to the other terminal of the spark coil 22. When the switch 24 is closed, a circuit from the transformer through the 10 ignition plug is completed resulting in a spark for igniting the fuel.

For operating the switch 24, I provide a stationary piston 28 upon which a cylinder 29 is reciprocably mounted. The upper end 15 of this cylinder is closed and is fitted with a ball check valve 30 which permits air to be drawn in between the upper ends of the piston and cylinder when the latter is raised relative to the piston. Downward movement 20 of the cylinder causes the air thus confined to be expelled between the sides of the piston and cylinder. As gravity is the only force provided for lowering the cylinder, the air will expel very slowly and retard the downward movement of the cylinder so that its down stroke will consume a predetermined 25 time period.

The lower end of the cylinder 29 abuts against the contact arm 25 and normally 30 holds the switch 24 open. When the cylinder is elevated the arm 25 instantly contacts with the arm 26 to close the switch and closes the circuit through the ignition plug. As soon as the cylinder is elevated it is released 35 and permitted to slowly move downwardly to its normal position. Just prior to reaching the lower end of its travel, the cylinder will engage the arm 25 and open the switch 24 and thus open the circuit through the ignition plug 23. The retarded action of the cylinder and the switch 24 causes the spark to continue a predetermined length of time 40 after the valve has opened and the circuit through the solenoid discontinued. This insures that the fuel delivered to the furnace 45 will have ample opportunity to ignite.

It should be stated that the cylinder is elevated simultaneously with the opening of the valve. This is accomplished by fitting 50 the valve shaft with a cam 30^a which engages a push rod 31^a which in turn engages a lateral projection on the cylinder. During the first quarter revolution of the valve shaft which is caused by a circuit being completed through the solenoid as described, the cam raises and lowers the push rod 31^a to elevate the cylinder. The instant the rod 31^a moves upwardly, the cylinder is elevated 55 sufficiently to cause the contact arm 25 to contact with the arm 26 and close the circuit through the ignition plug. This circuit will remain closed until the cylinder moves downwardly an amount necessary to break the contact between the arms 25 and 26 and thus 60 open the ignition circuit.

It should be stated that the valve controlling circuit is controlled by a push button type of switch as it is only necessary to close the circuit through the solenoid for an instant in order to open the valve. However, 70 the ignition circuit remains closed for a period after the valve opening circuit is open due to the delayed action of the cylinder which operates the switch 24.

To indicate the position of the valve, two 75 lamps 31 and 32 are provided. One side of each lamp connects with the lead which connects one side of the main switch with the transformer. The other side of the lamps are connected to independent switch plates 80 33 and 34. These plates are adapted to be engaged by protuberances on the valve shaft as the latter is rotated. For example, when the main switch is closed to move the valve from closed to first open position, the circuit 85 will be completed through both of the lamps 31 and 32 because both of the plates 33 and 34 will be electrically connected with the valve shaft to complete the circuits. When the main switch is closed a second time to 90 place the valve in second open position, only the circuit through the lamp 32 will be completed due to the position of the protuberances which are adapted to contact with the plate 33. Likewise when the valve 95 is turned to third position, the projection on the shaft will engage the plate 34, thus closing the circuit through the light 31 and opening that through the light 32. Thus the operator may by glancing at the two 100 indicator lights 31 and 32 be advised as to the position of the valve.

When the main switch is depressed for the fourth time, the valve will be closed and the circuits through both lights 31 and 32 105 will be opened indicating that the valve is closed.

In actual operation of the device, it will be assumed that the valve is in closed position. When the main switch is depressed 110 and released a circuit will have been closed through the solenoid for a sufficient period to elevate the core 16 thereof and impart a quarter revolution to the valve shaft 14 through the medium of the gear 15, the pawl 115 and ratchet 18 and 19. During this quarter revolution, the cam 30^a will reciprocate the push rod 31^a to elevate the cylinder 29. As previously described, the elevation of the cylinder 29 permits the contact arm 25 to 120 engage the arm 26 and complete the ignition circuit through the ignition plug 23, thus causing the spark to ignite the fuel admitted to the burner of the furnace through the valve 10.

Simultaneously with the turning of the valve shaft, circuits will be completed 125 through the switches 33 and 34 to light the lamps 31 and 32 indicating that the valve is in first open position.

As soon as the cylinder is raised it is released by the push rod 31^a and allowed to travel slowly downwardly. The period of its travel back down to normal position determines the length of time during which the spark is continued at the ignition plug for ignition purposes. As it reaches the lower end of its downward stroke, the cylinder contacts with the contact arm 25 and, as described, opens the switch 24, thus breaking the circuit through the ignition plug 23.

It should be stated that the time interval desired for a continued spark may be any length desired and is determined by the construction of the cylinder 29 and the piston 28. It is to be understood that other means may be substituted for the cylinder 29 and the piston 28 for causing retarded opening of the ignition circuit and for delaying thereof for a predetermined period after the valve operating circuit has been discontinued.

The second time the main switch is closed, the valve is rotated a second quarter revolution to place it in second open position which will be indicated by the lights 31 and 32 as described. Likewise the third and fourth successive times the main switch is closed will operate the valve to place it in third open position and close it. These positions of the valve will be likewise indicated by the lights 31 and 32. It should be stated, however, that the second, third and fourth operations of the switch will affect only the valve operating circuit, the ignition circuit being closed and opened on every first closing of the valve operating circuit.

From the foregoing it is obvious that the system I have provided will prevent the fuel valve from being opened and improper ignition supplied for igniting the fuel. Prior to my invention the ignition circuit was closed only during the period that the valve controlling circuit was closed. This length of time depended upon how long the operator maintained the main switch depressed. Therefore, the time of duration of the spark was sometimes insufficient to ignite the fuel, thereby permitting the furnace to fill with unburned gases. By my invention, however, the length of the duration of the spark is constant regardless of the length of time that the valve operating circuit is closed. This insures that the fuel will be ignited.

While I have shown the preferred form of my invention, it is to be understood that various changes in its construction may be

made by those skilled in the art without departing from the spirit of the invention as defined in the appended claims.

Having thus described my invention, what I claim and desire to secure by Letters Patent is:

1. A furnace ignition system including a fuel control valve controlling the supply of fuel delivered to the burners of a furnace, electrically actuated means for operating said control valve, a normally open main electrical circuit for operating said means, said valve being normally closed and adapted to be opened to progressively decreasing degrees in successive steps, each step occurring upon the closing and opening of the main circuit whereby by successively closing and opening said main circuit said valve will be advanced through its cycle of operation, a second circuit for creating an ignition spark to ignite fuel delivered to the burners of the furnace, means actuated by the closing of the main circuit at the commencement of the cycle of operation of the valve for closing the second circuit, means for automatically opening the second circuit independently of the main circuit and after a predetermined time period has elapsed, further opening and closing of the main circuit during the remaining portion of the cycle of operation of the valve unaffected by the second circuit.

2. A furnace ignition system including a normally closed fuel control valve for supplying fuel to the burners of a furnace, said valve adapted to be operated step by step through a certain cycle from closed position through open positions to a closed position, electrically actuated means for operating said valve step by step, a normally opened main electrical circuit for said means, each closing and opening of said main circuit moving said valve through one step of its cycle of operation, a normally opened ignition circuit for creating an ignition spark for igniting the fuel delivered to the burners of the furnace, means actuated by the closing of the main circuit during the first step of the cycle of operation of the valve for closing the second circuit, means for maintaining said second circuit closed for a predetermined length of time and then opening it, the closing of said second circuit being effected by closing the main circuit when advancing the valve through its first step of its cycle of operation only.

FREDERICK P. TERRY.
